ABSTRACT

A device adapted to travel up, down or horizontally on the side of vertical walls, having means to adhere to said wall, power means and traction means. In one form of this invention a magnet is employed to cause the device to adhere to a ferrous wall, the magnet being spaced a slight distance from said wall. Rubber tires are provided on the wheels for traction. In another form of this invention rubber coated magnetic wheels are used. In another form rubber coated magnetic treads are used. In another form of the magnetic climbing devices the power means may be omitted and the devices are adapted merely for climbing down on ferrous walls, they being drawn downwardly through the force of gravity. In another form the climbing device uses suction means to enable it to cling to a wall. This device can be used in air or under-water. In this form a pump is used to create a low pressure area between said device and said wall.

FIG. 1

FIG. 7

FIG. 8

FIG. 10

FIG. 9

WALL CLIMBING DEVICES

This invention relates to an improvement in wall climbing devices. More particularly, it relates to a device which is adapted to climb vertical walls and travel across ceilings without the use of tracks or other external holding devices. This invention uses a means to cause it to adhere to a vertical wall and also a means to propel it on said wall. This invention can find application in toys as well as in more serious work-performing applications.

In one form the invention is in the form of a wall climbing toy, the outer covering being in the form of a banana, for example, or in the form of a vehicle, or a large insect or a rodent.

In the work-performing category, it can be combined with such work-performing devices as sandblasting equipment, wall and ceiling washing equipment, etc. This invention can even be used in work-performing duties under-water in which it can attach itself to, and move around on, the hulls of ships, even though such ship may be in motion.

This invention uses two main features to accomplish its wall-climbing ability. One of the features is its ability to attach itself to a vertical wall and the other feature is its ability to propel itself along said vertical wall. In one method, magnetic means are used to enable the device to adhere to a ferrous vertical wall. In another method, suction means are used to enable the device to adhere to a vertical wall made of any material.

It is an object of this invention to provide wall climbing devices with means for adhering to a vertical wall.

It is also an object to provide wall climbing devices with means for propelling said device along said vertical wall.

It is also an object to provide wall climbing devices with magnetic means for adhering to a vertical ferrous wall.

It is also an object to provide wall climbing devices with suitable traction means for traveling along said vertical wall.

It is also an object to provide wall climbing devices with suction means for adhering to a vertical wall.

This invention contemplates other objects, advantages and features which will become more fully apparent from the following detailed description taken in conjunction with the accompanying drawings which illustrate preferred embodiments and in which:

FIG. 1 is a cut-away side view of this invention, showing a ferrous wall and a magnet which is interposed between the wheels of the climbing device to cooperate with said wall.

FIG. 2 is a partially cut-away top plan view of the device shown in FIG. 1.

FIG. 3 is a cross-sectional end view of the device shown in FIGS. 1 and 2 taken along lines III-III in FIG. 2.

FIG. 4 is another form of this invention in which the wheels are magnetic.

FIG. 5 is a partially cut-away top plan view of the device shown in FIG. 4.

FIG. 6 is a cross-sectional end view of the device shown in FIGS. 4 and 5 taken along lines VI-VI in FIG. 5.

FIG. 7 shows a side view of another form of this invention which uses magnetic caterpillar treads. The body covering is not shown.

FIG. 8 is a partially cut-away top plan view of the device shown in FIG. 7.

FIG. 9 is a front end view of the device shown in FIGS. 7 and 8 taken substantially along lines IX-IX in FIG. 8.

FIG. 10 is an enlargement of a portion of a drive wheel of the device shown in FIG. 7 which also shows a partial cross-section of a portion of the magnetic tread.

FIG. 11 shows a cut-away side view of another form of this invention which uses a suction method to adhere itself to a vertical surface.

FIG. 12 is a cut-away top plan view of the device shown in FIG. 11.

FIG. 13 is a top plan view of a portion of the device shown in FIGS. 11 and 12 showing the evacuation rotor shown in FIG. 11 and taken along lines XIII-XIII in FIG. 11.

Referring to FIGS. 1, 2 and 3 there is shown a wall climbing device 1 which is constructed according to the principals of this invention. The form of the outer covering 9 is optional and in this case is in the form of a banana. The climbing device 1 is provided with a magnet 10 which causes the said device 1 to adhere to a vertical wall 11 of ferrous material. The magnet 10 is suitably spaced 12 about one-sixteenth inch to one-eighth inch from the wall 11. This spaced distance 12 provides sufficient magnetic strength to cause the device 1 to cling to the ferrous wall 11. If no space, as 12, were provided the magnet 10 would cling physically to the ferrous wall 11 and upward travel would be impeded or made impossible due to friction. The slight spacing 12 provides sufficient magnetic attraction to the vertical ferrous wall 11 without restricting forward motion of the device 1. If too much spacing is provided between the magnet 10 and the ferrous wall 11 the magnetic attraction between the magnet 10 and the wall 11 would be weak and the device 1 would drop to the floor.

The device 1 is provided with a spring wound motor 13 (shown in block form) which drives the propelling wheels 14 and 15 which cause the device 1 to climb the wall 11.

The motor 13 is comprised of a wind-up key 16 which compresses the spring (not shown) which drives a series of gears (not shown) in the motor 13. A speed control governor (not shown) is provided at the end of the gear train to limit and control the traveling speed of device 1. The speed control governor can be in the form of a paddle which fans against the resistance of the surrounding air. One of the gears in the gear train drives a drive shaft 17 which in turn drives worm gears 18 and 19 which are affixed to the ends of drive shaft 17. Worm gears 18 and 19 in turn drive drive gears 20 and 21 which are affixed to front axle 22 and rear axle 23, respectively. Front wheels 14 are affixed to front axle 22 and rear wheels 15 are affixed to rear axle 23. The periphery of the wheels 14 and 15 are provided with a soft rubber material 24 which provides traction for the wall climbing procedure. The coating 24, in essence, forms the tires 24 for the wheels 14 and 15. Without the tires the wheels 14 and 15 would spin and there would be no forward traction. A start lever 25

can be provided in the motor 13 to start and stop the motor 13.

In operation, when it is desired to operate the wall climbing device 1, the wind-up key 16 is turned to compress the coiled-up leaf spring (not shown). The device 1 is then placed on the vertical surface of a ferrous wall, as 11, and is held there by the magnetic attraction between the magnet 10 and the ferrous wall 11. The start lever 25 is then moved and the device 1 starts to climb the wall 11 through the rotation of wheels 14 and 15. The motor 13 can be calibrated to drive the device 1 a distance of three or four feet at a rate of about one foot per second. The climbing device 1 is also capable of traveling horizontally on a vertical surface and even downwardly. In the event that the device 1 passes beyond the edge of the ferrous wall, and any two adjacent wheels slip past the said edge, the device 1 is prevented from falling by the magnet 10 which immediately 'sticks' to the wall 11. The magnet 10, in this case, also serves as a braking means and a holding means.

I have made a prototype of the device 1 by using a low-mass high-flux magnet and a two wheel drive. With this arrangement, device 1 performed very satisfactorily. Four wheel drive, as shown in FIGS. 1 and 2, may be used if desired. If not, one end of drive shaft 17 may be omitted along with the respective worm gear and drive gear. The drive may be front wheel drive or rear wheel drive. All parts are carried on a frame 26 which is secured in the body 9 of the device 1. Frame 26 is shown in part in FIG. 1. FIG. 3 shows a cross-sectional end view of device 1 showing the arrangement of the parts and particularly showing the relationship between the ferrous wall 11, the magnet 10, the wheel 14, the tire 24 and the space 12 between the magnet 10 and the ferrous wall 11.

Referring to FIGS. 4, 5 and 6, there is shown another form of wall climbing device 40 which is similar in some respects to device 1, shown in FIGS. 1, 2 and 3. Device 40 omits the use of a centrally located magnet, as 10, as used in device 1, and uses, instead, magnetic wheels 41 and 42 which are also provided with traction producing tires 43. Device 40 also has an outer body form 44, a wind-up motor 45, worm gears 46 and 47 which drive drive gears 48 and 49 which are affixed to front and rear axles 50 and 51, respectively. The wheels 41 and 42 are affixed to front and rear axles 50 and 51, respectively.

Referring to FIGS. 4 and 6, it is shown that the outer circumference 52 of the wheels 41 and 42 is spaced a slight distance from the ferrous wall 53. The distance is slight enough to allow maximum magnetic attraction between each of the magnetic wheels 41 and 42 and the ferrous wall 53, with the spacing there-between being occupied by the traction producing material or tires 43. If no traction producing tires, as 43, were provided the magnetic wheels 41 and 42 would spin through the force of the motor 45 and no forward motion of the device 40 would be achieved. Each of the axles, 50 and 51, may optionally be of ferrous material or magnetic material to cause a magnetic coupling between each set of wheels. For example, front axle 50 and front wheels 41 would form a magnetic unit with the wheels 41 serving as pole pieces to engage the (keeper) ferrous wall 53.

The operation of device 40 is the same as that of device 1 shown in FIGS. 1, 2 and 3. The key 54 is turned to wind-up the spring-wound motor 45, the device 40

is then placed on a vertical ferrous wall 53, such as a refrigerator or a cabinet, where it will adhere. The start lever 55 is then moved to the "ON" position which causes the motor 45 to start turning the wheels 41 and 42 which in turn causes the device 40 to climb the vertical wall 53. The frame 56 is shown in part in FIG. 4.

FIGS. 7, 8, 9 and 10 show another form of this invention in which the climbing device 70 is provided with 10 a pair of caterpillar-type threads 71 which have small magnets 72 embedded in the tread lugs 73. The treads 71 are molded as a continuous rubber loop 74 with the magnets 72 molded thereon with a thin rubber coating 75 molded on the surface of the magnets 72 to provide 15 traction on the vertical ferrous wall 76. An enlargement of the wheel 82 and a portion of the magnetic tread 71 are shown in FIG. 10. The climbing device 70 comprises a wind-up motor 77, a frame 78, worm gears 79, drive gears 80 which are affixed to axles 81 and 20 drive wheels 82 which are affixed to axles 81 and which support the magnetic treads 71. Referring to FIGS. 9 and 10, the drive wheels 82 have a flat circumferential tread bearing surface 83 and flanges 84 on the sides to prevent the magnetized rubber tread 71 from slipping 25 off the said wheels 82. The body covering is not shown for device 70 and may be of any suitable shape desired. The number of magnets 72 may be of any quantity to support the weight of device 70 on the vertical wall 76. The frame 78 is shown in part in FIG. 7, and not at all 30 in FIG. 10. The magnetic tread 71 may optionally be of a type in which magnetic particles are embedded in the rubber tread (not shown).

In operation, the key 85 is turned to wind-up the 35 motor 77. The device 70 is then placed on a vertical ferrous wall, such as 76. The magnets 72 in the lugs 73 attract to the ferrous wall 76 and support the device 70 thereon. The start lever 86 is then moved to the "ON" position and the device 70 proceeds to climb the ferrous wall 76 at an even, controlled, speed. Although 40 the devices shown in FIGS. 1 through 10 are capable of climbing up a vertical wall, they are also capable of climbing down a wall or even traveling horizontally on the vertical surface. If desired, the motor means 13, 45 and 77 can be omitted and the devices 1, 40 and 70 can be used solely for climbing down a wall through their own weight. A governor means in the form of a gear train can be used to control the downward speed of the devices 1, 40 and 70.

FIGS. 11, 12 and 13 show another form of wall climbing device 100. Device 100 is adapted to cling to a vertical wall through the use of suction power. Device 100 can adhere to a substantially smooth wall made of any material and can be adapted to operate in air or under water. The air or water will hereinafter be referred to as fluid. The device 100 has a leak-proof body 101. An opening 102 is provided, preferably at the top side 103, through which fluid 104 is constantly being ejected. A fluid ejecting rotor 105 is fitted in the opening 102 which is powered by an electric motor 106 which receives current from batteries 107. The motor 106 also drives a drive shaft 108 through gears 109 and 110. The drive shaft 108 in turn drives wheels 111 and 112 through gears 113 and 114. The wheels 111 and 112 are provided with suitable traction producing tires 115 or other means. A narrow space 116 is provided 55 between the lower edge 117 of the skirt 118 of the body 101 and the proposed vertical surface to be climbed. 60

The space 116 provides clearance so that the edge 117 of the body 101 will not bind or rub on the surface 120 of the vertical wall 121. The motor 106, the batteries 107, wheels 111 and 112 and other parts are supported by a suitable frame 122 which is secured in the body 101. The frame 122 is shown in portion in FIG. 11.

In operation, the device 100 is placed on a vertical wall, such as 121, with the bottom side 117, which has the wheels 111 and 112, facing the wall 121. The bottom side 117, which faces the wall 121, can be either partially or completely open. The switch 123 is then moved to the "ON" position which completes the electrical circuit. The current from the batteries 107 energizes the motor 106 causing the armature therein (not shown) to rotate. The pump rotor 105, which is attached to armature shaft 124, revolves at a high rate of speed, thereby ejecting fluid 104 out of the body cavity 125 and into the space 126 externally of said device 100. The path of the expelled fluid 104 is shown by the broken arrow. A low pressure area 127 is created between the leak-proof body 101 of the device 100 and the wall 121. The fluid 126B in the external space 126, having a pressure greater than the internal fluid 104, exerts its pressure on the body 101 of the device 100 forcing it against wall 121. A certain amount of fluid 126A will leak through the space 116, but as long as the rotor 105 is turning, the external fluid pressure 126B will always be greater than internal fluid pressure 104. As the motor 106 operates, it drives the drive shaft 108 which rotates the wheels 111 and 112 causing the device 100 to travel along the wall 121. The faster the rotor 105 rotates the greater will be the suction between the device 100 and the wall 121 and the greater will be the ability of the device 100 to cling to the wall 121. FIG. 12 shows a partially cut-away top plan view 35 of the device 100 showing the arrangement of the power means. FIG. 13 shows a portion of the top side 103 of the device 100 showing the pump rotor 105.

The climbing devices shown in FIGS. 1 through 13 have been shown having self-contained power means. It is possible for the power means to be located remotely from the devices 1 through 13 with power being supplied by conduit or by conductor means (tube or electrical wires).

It is also possible that the devices shown in FIGS. 1 through 13 can have a self-contained electrical (or other) power means and that the operation (start & stop) of the device can be controlled remotely by a radio transmitter.

As stated in the foregoing, although the devices shown in FIGS. 1 through 13 can be in the form of a toy, they could also be in the form of work-performing climbing devices. The power means in all the devices shown in FIGS. 1 through 13 can be electrical and each device can be coupled with some form of work-performing equipment. For example, a climbing device shown herein can carry a welding-torch for welding metal plates which might be comparatively inaccessible

by other means. Or a climbing device can carry a cutting-torch for cutting metal plates. Or a climbing device can carry a sand-blasting head on a vertical wall or on a ceiling. Or a climbing device can carry a wall-painting device (spray or roller). A climbing device can even be made buoyant so that it can float on water and as it approaches a ship it can climb upward on the hull of the ship. All these work-performing climbing devices can be remotely powered and/or remotely controlled. As shown, there are countless types of work-performing duties that can be performed by the climbing devices shown in this invention.

It will be appreciated that other modifications and variations may be effected without departing from the 15 spirit and scope of the novel concepts of this invention.

I claim as my invention:

1. In a device adapted to move along a planar vertical surface of a member of magnetic material, a frame structure, a pair of wheel means journaled on said frame structure on spaced parallel axes for engagement of peripheral portions thereof with spaced portions of a planar surface, and permanent magnet means carried by said frame structure in a manner such as to be spaced a certain spacing distance from a planar surface engaged by said wheel means, said certain spacing distance being large enough to avoid frictional engagement between said permanent magnet means and a planar surface engaged by said peripheral portions of said wheel means and being small enough to provide magnetic attraction to a member of magnetic material sufficient to maintain engagement between said peripheral portions of said wheel means and a planar vertical surface of a member of magnetic material.
2. In a device as defined in claim 1, drive means carried by said frame structure and drivingly connected to at least one of said pair of wheel means.
3. In a device as defined in claim 2, each of said wheel means including peripheral coating means of a soft rubber material for increased traction.
4. In a device as defined in claim 3, said pair of wheel means including inner wheels of magnetic material forming part of said permanent magnet means, said coating means being on said inner wheels and being effective to provide said certain spacing distance.
5. In a device as defined in claim 1, said permanent magnet means being fixedly carried by said frame structure between said wheel means to be spaced said certain spacing distance from the portion of a planar surface between said pair of wheel means.
6. In a device as defined in claim 5, drive means carried by said frame structure and drivingly connected to at least one of said pair of wheel means, each of wheel means including peripheral means of a soft rubber material for increased traction.
7. In a device as defined in claim 6, said drive means being a wind-up type spring motor.

[57] ABSTRACT

A device adapted to travel up, down or horizontally on the side of vertical walls, having means to adhere to said wall, power means and traction means. In one form of this invention a magnet is employed to cause the device to adhere to a ferrous wall, the magnet being spaced a slight distance from said wall. Rubber tires are provided on the wheels for traction. In another form of this invention rubber coated magnetic wheels are used. In another form rubber coated magnetic treads are used. In another form of the magnetic climbing devices the power means may be omitted and the devices are adapted merely for climbing down on ferrous walls, they being drawn downwardly through the force of gravity. In another form the climbing device uses suction means to enable it to cling to a wall. This device can be used in air or under-water. In this form a pump is used to create a low pressure area between said device and said wall.

**REEXAMINATION CERTIFICATE
ISSUED UNDER 35 U.S.C. 307**

THE PATENT IS HEREBY AMENDED AS
INDICATED BELOW.

Matter enclosed in heavy brackets **[ ]** appeared in the patent, but has been deleted and is no longer a part of the patent; matter printed in italics indicates additions made to the patent.

ONLY THOSE PARAGRAPHS OF THE
SPECIFICATION AFFECTED BY AMENDMENT
ARE PRINTED HEREIN.

Column 3, lines 36-65:

Referring to FIGS. 4, 5 and 6, there is shown another form of wall climbing device 40 which is similar in some respects to device 1, shown in FIGS. 1, 2, and 3. Device 40 omits the use of a centrally located magnet, as 10, as used in device 1, and uses instead, *permanent-magnetic* wheels 41 and 42 which are also provided with traction producing tires 43. Device 40 also has an outer body for 44, a wind-up motor 45, worm gears 46 and 47 which drive drive gears 48 and 49 which are affixed to front and rear axles 50 and 51, respectively. The wheels 41 and 42 are affixed to front and rear axles 50 and 51, respectively.

Referring to FIGS. 4 and 6, it is shown that the outer circumference 52 of the wheels 41 and 42 is spaced a slight distance from the ferrous wall 53. The distance is slight enough to allow maximum magnetic attraction between each of the magnetic wheels 41 and 42 and the ferrous wall 53, with the spacing there between being occupied by the traction producing material of tires 43. If no traction producing tires, as 43, were provided the magnetic wheels 41 and 42 would spin through the force of the motor 45 and no forward motion of the device 40 would be achieved. Each of the axles, 50 and 51, may optionally be of ferrous material or **[magnetic material]** a *magnet* to cause a magnetic coupling between each set of wheels. For example, front axle 50 and front wheels 41 would form a magnetic unit with the wheels 41 serving as pole pieces to engage the (keeper) ferrous wall 53.

**AS A RESULT OF REEXAMINATION, IT HAS
BEEN DETERMINED THAT:**

Claims 1 and 2 are now disclaimed.

Claim 3 is cancelled.

Claims 4-6 are determined to be patentable as amended.

Claim 7, dependent on an amended claim, is determined to be patentable.

New claims 8-15 are added and determined to be patentable.

4. In a device as defined **[in]** by claim **[3]** 13, said pair of wheel means including inner wheels of *permanent-magnetic* material forming part of said permanent magnet means, said coating means being on said inner

wheels and being effective to provide said certain spacing distance.

5. In a device as defined in claim **[1]** 13, said permanent magnet means **[being]** fixedly carried by said frame structure between said wheel means in a manner such as to be spaced said certain spacing distance from the portion of a planar surface engaged by said wheel means between a pair of wheel means.

6. In a device as defined in claim 5, drive means carried by said frame structure and drivingly connected to at least one of said pair of wheel means **[each of wheel means including peripheral means of soft rubber material for increased traction]**.

8. A device as defined by claim 5 wherein said magnet means is of a low-mass high-flux kind.

9. A wall-climbing toy adapted to roll on and against a substantially planar vertical surface of a member of magnetic material comprising:

a. a frame structure,

b. four wheels and two axles journaled on said frame structure on spaced axes for rolling engagement of said wheels with spaced portions of said planar surface,

c. drive means carried by said frame structure and drivingly connected to at least one of said wheels,

d. each of said wheels having soft rubber tires, and

e. permanent magnet means carried by said frame structure in a manner such as to be spaced a certain spacing distance from a flat surface engaged by said tires, said certain spacing distance being large enough to avoid frictional engagement between said permanent magnet means and a substantially planar surface of a member of magnetic material engaged by said tires and being small enough to provide magnetic attraction sufficient to maintain an engagement of said wheels with such a planar surface.

10. A toy as defined by claim 9,

f. wherein said magnet means comprises a magnet of a low-mass, high-flux kind situated wholly between said axles.

11. A toy as defined by claim 10,

g. wherein said member is a ferrous wall.

12. In a device as defined in claim 4, drive means carried by said frame structure and drivingly connected to at least one of said pair of wheel means, each of said wheel means including peripheral means of a soft rubber material for increased traction.

13. In a device adapted to move along a planar vertical surface of a member of magnetic material,

a. a frame structure,

b. a pair of wheel means journaled on said frame structure on spaced parallel axes for engagement of peripheral portions thereof with spaced portions of a planar surface,

c. each of said wheel means including peripheral coating means of a soft rubber material for increased traction, and

d. permanent magnet means carried by said frame structure in a manner such as to be spaced a certain spacing distance from a planar surface engaged by said wheel means, said certain spacing distance being large enough to avoid frictional engagement between said permanent magnet means and a planar surface engaged by said peripheral portions of said wheel means and being small enough to provide magnetic attraction to a member of magnetic material sufficient to maintain engagement between said peripheral por-

tions of said wheel means and a planar vertical surface of a member of magnetic material.

14. In a device as defined in claim 5, at least one of said wheel means including peripheral coating means of a soft

rubber material for increased traction.

15. In a device as defined in claim 14, drive means carried by said frame structure, and drivingly connected to said one of said wheel means.
